CIRCUIT INTERRUPTER

James M. Cumming and Samuel H. Boden, Turtle Creek, Pa., assignors to Westinghouse Electric Corporation, East Pittsburgh, Pa., a corporation of Pennsylvania

Application February 24, 1947, Serial No. 730,518

16 Claims. (Cl. 200—82)

1

The invention relates to circuit interrupters of the type adapted for high-speed reclosing operations. Circuit interrupters of this type usually are connected directly to their closing means to permit instantaneous reclosing of the interrupter without waiting for a retrieving or resetting operation. It is sometimes necessary to close the circuit interrupter manually for example, when the power operated closing means becomes inoperative, or during inspection and maintenance. Manually operated closing means is provided for this purpose.

It is important for the safety of the operator and also for the safety of the apparatus that the interrupter should be trip-free of the manually operated closing means. That is, the interrupter should be capable of moving to the open position independently of the manual closing means if a fault is still present when the interrupter is manually closed in.

One object of the invention is to provide a circuit interrupter having a closing means at all times connected thereto and capable of being manually closed with novel means for tripping the interrupter free of the manual closing means.

Another object of the invention is to provide a circuit interrupter having power operated closing means and which may be manually closed wherein the interrupter is trip-free of the manual closing means but is non-trip-free of the power closing means.

Another object of the invention is to provide a circuit interrupter which is non-trip-free of the operating mechanism with means for rendering the interrupter trip free on a manual closing operation.

Another object of the invention is to provide a circuit interrupter of the fluid motor operated type having latch means for releasably restraining the interrupter in closed position with means connected to and operated by said latch means for quickly dumping the fluid pressure from the motor.

Another object of the invention is to provide a circuit interrupter according to the preceding paragraph wherein the dump valve is opened when the latch moves to unlatching position and is closed when the latch moves to latching position.

The novel features that are considered characteristic of the invention are set forth in particular in the appended claims. The structure and mode of operation of the invention, together with additional objects and advantages thereof will be best understood from the following de-

2

tailed description of several embodiments thereof when read in conjunction with the accompanying drawings, in which:

Figure 1 is a vertical sectional view of a circuit interrupter operating mechanism embodying the invention, taken substantially along line I—I of Fig. 2, the circuit interrupter being shown schematically.

Fig. 2 is a plan view of the circuit interrupter operating mechanism.

Fig. 3 is a detail sectional view taken on line III—III of Fig. 2 of the electromagnetically operated inlet valve for admitting compressed gas to the fluid motor to close the circuit interrupter.

Fig. 4 is an elevational view partly in section of a modification of the latching mechanism.

Fig. 5 is a vertical sectional view taken on line V—V of Fig. 1, showing the dump valve.

Referring to Figs. 1 and 2 of the drawings, the circuit interrupter, illustrated schematically at 7, may be of any conventional type, either the oil break, air break or gas blast type. The circuit interrupter, as shown schematically in Fig. 1, comprises stationary contact means 9 and cooperating movable contact means 11. The circuit interrupter is biased open by means of an accelerating spring 13 and is connected to the operating mechanism 15 by any suitable connection shown schematically by a pivoted lever 17 and operating rod 19.

The operating mechanism comprises a casting 21 formed to provide an operating cylinder 23 and a top portion thereof which closes the upper end of the cylinder and serves as a support for some of the parts. An operating piston 25 is disposed for reciprocal movement within the cylinder 23 and is adapted to be operated by fluid pressure to effect closing of the circuit interrupter. A bracket 26 (Fig. 2) is secured to the casting 21 by any suitable means as, for example, by welding. The bracket 26 is provided for the purpose of mounting the operating mechanism on a suitable support such as the wall of a housing or an enclosure. The angular right hand formed end 27 of the bracket 26 and a bracket 28 (Fig. 2) secured to the casting 21 are provided with fixed pivot pins 29 in axial alignment upon which is pivotally mounted a pair of spaced outer levers 31. At their left ends the outer levers are pivotally connected to a pair of inner levers 33 by means of a pivot pin 35. The inner and outer levers are suitably spaced apart by spacers 37.

Near their right hand ends (Figs. 1 and 2) the

inner levers carry a pin 39 upon which is mounted a latch roller 41 which is engaged by a pivoted latch member 43 to releasably restrain the right end of the inner levers in the closed circuit position as shown in Figure 1. A main tripping latch 45 engages a latch roller 47 mounted on the pin 35 which joins the left hand ends of the inner levers 33 and the outer levers 31 to releasably restrain the left ends of the levers in the position shown. The latch 43 is pivoted on a pin 49 supported in the formed end 27 of the bracket 26 and in the bracket 28 and is biased in latching direction by means of a spring 51. The spring 51 surrounds a spring guide 53 and is seated in a spring seat in plate 55 suitably secured, as by welding, to the casting 21. The spring guide 53 comprises a bolt having a rounded head engaging a shoulder on the latch 43. The lower end of the spring guide 53 extends downwardly through a suitable opening in the plate 55 and a nut 57 is screwed onto the lower end to act as a stop limiting the movement of the spring guide.

The main tripping latch 45 is mounted on a pin 59 supported between a pair of spaced brackets 61 and 63 suitably secured to the main casting 21. The main tripping latch 45 is biased in latching direction by means of a spring 65 compressed between a cup-shaped spring seat 67 and the rounded head of a spring guide 69. The spring seat 67 is rigidly secured in an opening in a cross member 71 joining the outer ends of the brackets 61 and 63. The main latch 45 is the slip-off type, that is, it will not of itself restrain the levers 31 and 33 against the bias of the accelerating spring 13, but is held in latching position by means of an intermediate latch 73 which, in turn, is restrained in latching position by a trigger latch 75. The intermediate latch 73 is pivotally supported on a pin 77 mounted in the brackets 61 and 63 and biased in latching direction by means of a spring 79 compressed between the latch 73 and a cross member 81 rigidly secured to the brackets 61 and 63.

The trigger latch 75 comprises a part of a tripping electromagnet indicated generally at 83 (Fig. 1). The tripping electromagnet comprises an E-shaped core member 85 mounted by means of a U-shaped bracket 87 secured by means of a bolt 88 to the casting 21. An energizing winding 89 surrounds the center leg of the core member. A channel-shaped armature 91 has its spaced side members pivotally supported on the bracket 87 by means of a pivot pin 93 in the two side members of the bracket 87. The cross member of the armature is formed upwardly to form the trigger latch 75 and the armature is biased by means of a spring 95 to latching position.

The tripping electromagnet 83 may be energized from any suitable source as, for example, a conventional fault relay. When energized, the electromagnet attracts its armature 91 and moves the trigger latch 75 to unlatching position which permits the powerful accelerating spring 13 to force the main latch 45 clockwise about its pivot 59 to unlatching position against the force of the spring 65. The unlatching movement of the main latch 45 moves the intermediate latch 73 to its unlatching position. Movement of the main latch 45 to unlatching position releases the left ends of the inner and outer levers 33 and 31 whereupon the force of the accelerating spring 13 starts the levers as a unit in a clockwise direction, the outer levers 31 pivoting about their pivot pins 29 (Fig. 2) and the inner levers 33 piv-

otating about the pin 39 upon which the latch roller 41 is mounted. Very shortly after the start of the clockwise movement of the levers 31 and 33, a pin 97 carried by the inner levers 33 engages a projection 99 on the latch 43 and moves this latch to unlatching position. This permits the right hand ends of the inner levers 33 to move upwardly and the interrupter 7 to move to full open position.

The lower end of the operating rod 19 is connected to the inner levers 33 by means of a pin 101 supported in the levers and passing through an opening in a member 103 rigidly secured to the lower end of the rod 19. The operating rod 19 and the inner levers 33 are also connected by means of a piston rod 105 and a nut 106 to the operating piston 25. The enlarged upper end 107 of the piston rod 105 is slotted as at 109 to receive the member 103 and each of the side portions of end 107 is provided with a horizontal slot 111 embracing the pin 101 to thereby connect the piston to the levers 33 and to the operating rod 19. The piston rod is surrounded by a sleeve 113 which passes through a packing gland 115 in the top of the cylinder 23.

When the left hand end of the lever system 31-33 is released by the latch 45, the interrupter 7, the breaker rod 19 and the piston 25 start in the opening direction under the influence of the accelerating spring 13 with the lever system pivoting about the fixed pivots 29 (Fig. 2) and the pin 39. After the latch 43 is released by the pin 97 the right hand end of the inner lever 33 is free to move upwardly to the fully open position indicated at 33'. Immediately after the right end of the inner levers 33 are released by the latch 43 the left end of the lever system is restored to its latched position, the outer levers 31 pivoting about the fixed pivots 29 and the inner levers 33 pivoting in a counterclockwise direction about the pin 101. As soon as the latch 45 reengages the latch roller 47 the levers 33 continued to the open position 33' pivoting about the pin 35.

The means for effecting the relatching of the left end of the lever system comprises a pair of powerful springs 117 disposed one on each side of the lever system (Fig. 2) and having their left ends anchored by means of spring clips 119 to the ends of the pin 35 which pivotally connects the left ends of the levers 31 and 33. The right ends of the springs 117 are attached by means of spring clips 121 to the ends of a pin 123 which is engaged and restrained in the position shown in Fig. 1 by a dual latch 125. The springs 117 are not given an initial tension. The pin 123 is carried by the free ends of a pair of arms 127 pivotally mounted on the outer ends of the fixed pivots 29 outside of the outer levers 31. The latch 125 comprises a pair of spaced latch members pivotally supported on the pin 49 and secured together at their outer ends by means of a rod 129 which serves as a handle for manually operating the latch. The latch 125 is biased to latching position by means of a spring 131 compressed between a spring seat in the plate 55 and a spring guide 133 seated against the under side of the latch members 125. The mechanical arrangement is such that at the beginning of the opening movement of the left end of the lever system the springs exert a minimum force opposing the opening movement of the levers. When the latch 43 releases the right hand end of the inner lever 33, the springs 117 act to immediately restore the left end of the lever system to the latched position while the inner

levers rotate about the pivot 35 to the full open position.

In order to close the interrupter, compressed gas is admitted to the cylinder 23 above the piston 25 to drive the piston down and effect the circuit closing operation. Compressed gas is admitted to the cylinder by means of an electro-magnetically operated inlet valve mechanism shown generally at 135 (Figs. 2 and 3). The inlet valve mechanism comprises an inlet valve 137 mounted in a valve housing 139 suitably secured to the casting 21 near the upper end of the cylinder 23. The inlet valve 137 is biased to close an inlet port 141 in the housing 139 by means of a spring 143 seated in a spring seat in an air inlet chamber comprising a housing 145 secured to the housing 139. The inlet chamber is connected by means of a pipe 147 to a suitable source (not shown) of compressed gas. The inlet valve 137 is moved to the open position by means of an electromagnet 149 (Fig. 3) comprising a fixed core member 151 which is mounted on the valve housing 139 by means of brackets 153. The core member 151 is E-shaped and an energizing winding 155 is mounted on the center leg thereof. An armature 157 is secured to the upper end of a valve rod 159 which extends downwardly and has the inlet valve attached to the lower end thereof. Also fixed to the valve rod 159 is a normally open exhaust valve 161.

The winding 155 of the inlet valve electromagnet may be energized from any suitable source either by operation of a manual switch or by an auxiliary switch controlled by the interrupter mechanism. When energized, the electromagnet attracts and moves the armature 157 and the armature rod 159 downward to close the exhaust valve 161 and open the inlet valve 137. Opening of the inlet valve admits compressed gas to the cylinder 23 above the piston 25 and forces the piston downwardly to effect closing of the interrupter. During the closing stroke, the inner levers 33 are rotated in a clockwise direction about the pivot 35. Near the end of this operation the latch roller 41 engages the upper end of the latch 43 and moves the latch to the non-latching position. As soon as the mechanism reaches the fully closed position, the spring 51 acts to restore the latch 43 to latching position.

In the event that the interrupter is closed in with a fault still present in the circuit controlled by the interrupter, the tripping electromagnet 83 will immediately function to release the main latch and permit the interrupter to move to the open position. At this time, the closing charge of compressed gas is in the cylinder and, in order to effect quick reversal of movement of the mechanism and opening of the interrupter, it is necessary to quickly dump the closing pressure from the cylinder. For this purpose there is provided a large exhaust valve device 163 which is connected to and operated by the main latch 45. The dump valve device 163 comprises a casting 165 (Figs. 1 and 5) bolted to the top of the casting 21 in line with a large exhaust port 167 extending vertically through the top of the casting 21. Disposed in a large circular opening in the casting 165 is a dump valve 169 comprising spaced discs 171 rigidly connected by a plurality of integral cross bars 173. The left hand one (Fig. 1) of the discs 171 is provided with an ear 175 which is pivotally connected by means of a pivot pin 177 to a pair of links 179 disposed one on each side of the ear. The other ends of the links 179

are pivotally connected by means of a pivot pin 181 to the main latch 45.

When the tripping electromagnet 83 (Fig. 1) is energized to release the main latch 45, as was previously described, the lever system comprising the inner levers 33 and the outer levers 31 are released and move a short distance in a clockwise direction respectively about the pin 39 and the fixed pivots 29. During this movement the latch roller 41 cams the latch 45 clockwise about its pivot 59 which movement, through the links 179, moves the dump valve 169 toward the left (Fig. 1) to the open position indicated by dot and dash lines at 169. This opens a large area through which the closing pressure in the cylinder may be quickly dumped to atmosphere to permit high speed opening of the interrupter.

It will be remembered that at the beginning of the opening movement, the left hand end of the lever system 31-33 moves a short distance in opening direction and then, after the latch 43 is operated by the pin 97 to release the right end of the inner levers 33, the springs 117 act to restore the left end of the lever system to the latched position. During the movement of the left end of the lever system, the latch roller 41 moves upwardly along the edge of the latch 45 to approximately the position indicated at 41' but does not move out of engagement with the latch 45. It will thus be seen that the roller 41 holds the latch 45 in unlatching position and consequently holds the dump valve 169 in the open position during the time interval the left-end of the lever system is out of latched position. When the right hand end of the inner levers 33 is released by the latch 43 through the action of the pin 97 and the springs 117 have restored the left hand end of the lever system to the full line position (Fig. 1), the spring 65 moves the latch 45 to latching position and, through the links 179, moves the dump valve 169 to closed position. It will thus be seen that the dump valve is open when the main latch is in the unlatched position and is closed when the main latch is in the latching position.

It is at times necessary to close the circuit interrupter manually, for instance, when the power operated closing means becomes inoperative. Any suitable manual closing device may be utilized to close the breaker, none being shown herein. A manual closing device of a type particularly adapted for closing circuit interrupters of the type disclosed in the instant application is shown in United States Patent 2,242,916, issued May 20, 1941 to H. G. MacDonald and assigned to the assignee of the instant application. This manually operated closing device consists of a jack of the screw type which, when mounted on the circuit interrupter mechanism, engages at one end a bracket 183 rigidly secured to the frame and the other end engages in notches 185 provided for that purpose in the right hand end of the inner levers 33. When the jack disclosed in the aforementioned patent is mounted on the interrupter mechanism, the screws are rotated manually and the travelling member of the jack draws the inner levers 33 down to the closed position where the roller 41 is engaged by the latch 43. During the manual closing operation, the levers 33 pivot about the pin 35 in the same manner as when closed by the power means.

When closing the interrupter manually, it is necessary, in order to protect the operator and the mechanism, to make the interrupter trip-free of the manual closing means so that should the

interrupter be manually closed in against a fault, it may be tripped and instantly moved to full open position independently of the manual closing device. This is effected by operating the manual latch 125 and holding the latch in non-latching position during the manual closing operation. This frees the pin 123 which normally restrains the right end of the springs 117 so that these springs restore the left end of the lever system when the latch 43 is released by the pin 97. With the manual closing device in position to close the breaker, the right hand end of the inner levers cannot move to the open position. But, with the latch 125 held in its non-latching position, the springs 117 are ineffective to restore the left end of the lever system to the latched position, hence, if the interrupter is manually closed in against a fault, the trip device 83 will function to release the latch 45 and the lever system will go to the open position indicated at 33a, the outer levers 31 pivoting about the fixed pivots 29 and the inner levers pivoting about the pin 39. During the trip-free opening operation the springs 117 and the arms 127 travel with the lever system in substantially the same relation as the parts appear in Fig. 1. This is due to the pin 123 extending across beneath the inner levers 33 which prevents movement of the arms 127 relative to the levers 33. When the interrupter is in its fully closed and latched position, the latch 125 is moved to its latching position by means of the handle 129 to reengage the pin 123.

In order to close the interrupter following an operation wherein the mechanism is tripped free of the manual closing device, it is first necessary to remove the manual closing device and then to reset the left end of the lever system to the latched up position. The latter is accomplished, after the manual closing device is removed, by moving the inner levers 33 to their open position indicated at 33'. During this movement, the inner levers 33 pivot counterclockwise about the pin 401 which is, at this time, in the open or raised position. The counterclockwise movement of the inner levers 33 about the pin 401 causes the outer levers 31 to move in the same direction about their fixed pivots 29 to reengage the latch roller 47 with the main latch 45. Thereafter, the interrupter may be closed manually by again mounting the manual closing device on the mechanism.

When the interrupter is tripped open from the fully closed position, as previously set forth, the main latch 45 is held by the roller 47 in the unlatched position until the inner levers 33 are released by the latch 43 and the roller 47 is restored to the latched position by the springs 117. During the time the latch 45 is held in unlatching position, a tail 187 thereon engages a surface 189 on the intermediate latch 73 thus holding this latch in unlatching position. Also the lower end 191 of the intermediate latch 73 is held in position above the latch 75. Thus the roller 47 maintains all of the latches 45, 73 and 75 in their unlatched positions until the roller 47 is restored to its latching position, whereupon the springs 65, 79 and 95 move their respective latches 45, 73 and 75 in sequence to their latching positions. When, however, the interrupter, being manually closed in against a fault, is tripped free of the manual closing means, and the entire lever system pivoting at its right hand end moves to the open position, the roller 47 moves past the end of the main latch 45 to the open position indicated at 47a. During this

operation the latch 45 will be restored to its latching position as soon as the roller 47 moves beyond the end of the latch. In order to permit the roller 47 to reengage the latch 45 during a closing operation following a trip-free operation, it is necessary to hold the intermediate latch in its unlatched position. This is accomplished by means of a holding lever 193 comprising a pair of spaced parallel levers disposed one on each side of the main latch 45 and pivoted on the pin 59. The lower ends of the holding levers 193 are rigidly connected by a cross stud 195 and is biased by means of a spring 197 in a counterclockwise direction. The spring 197 is compressed between a cup-shaped spring seat 199 rigidly secured in an opening in the cross member 71 and a collar 291 on a spring guide 203 which is slidable in an opening in the bottom of the spring seat and has a reduced end extending into an opening in the stud 195. A pin 295 carried between the inner lever 33 and engaging projections 297 on the outer lever 193 normally prevents counterclockwise movement of the holding lever 193.

When the lever system 31-33 moves the roller 47 beyond the end of the latch 45 during a trip-free operation, the latch 45 is restored to its latching position by the spring 65. The movement of the pin 295, however, permits the spring 197 to rotate the holding lever 193 counterclockwise to engage the stud 195 with the latch 73 and, since the spring 197 is stronger than the spring 79, the latch 73 is maintained in unlatching position. During a closing operation following a trip-free opening operation, the roller 47 engages and cams the latch 45 to unlatching position and then the pin 295 engages the projection 297 and moves the holding lever 193 to its non-holding position permitting the intermediate latch 73 to reengage the latch 45 when the latter moves into latching engagement with the roller 47.

Figure 4 of the drawings illustrates a modification of the latching and tripping mechanism. In the Figure 4 modification, the main latch 209 comprises a pair of spaced parallel latch levers pivoted on a pivot pin 211 mounted in the brackets 61 and 63, only the bracket 61 being shown in Fig. 4. The latch levers 209 are rigidly joined at their upper ends by an angular cross member 213 and, just below the member 213, carry a pin 215 upon which is mounted a latch roller 217 which cooperates with the latch roller 47 to releasably restrain the left hand end of the lever system 31-33 in closed position. In the latching position, the center of the latch roller 217 is slightly to the right of the vertical center line drawn through the center of the latch roller 47 and the center of the pivot pin 211 and consequently restrains the interrupter in the closed position with an exceedingly light tripping load. The position of the latch roller 217 relative to the latch roller 47 in the latched position is adjustable by means of an adjusting screw 219 threadedly mounted in a cross member 221 rigidly secured to the latch levers 209. The end of the screw 219 abuts against the latch roller 47 and the screw is locked in its adjusted position by means of a lock nut 223. For biasing the main latch to latching position, there is provided a spring 225 having one end attached to a rod 227 secured to and extending between the latch levers 209 and having the other end attached to a rod 229 mounted in the brackets 61 and 63. The main latch is moved in a counterclockwise

or tripping direction by means of a U-shaped trip member 231 pivotally supported on a pivot pin 233 mounted in the brackets 61 and 63, and biased in tripping direction by a powerful spring 235. The spring 235 has one end hooked over a rod 237 rigidly mounted between the two legs (only one being shown) of the trip member and the other end hooked over a spring stud 239 on one arm of a lever 241. The lever 241 is pivotally mounted on a pivot pin 243 supported in the brackets 61, 63, and the other arm of the lever 241 extends beneath the latch roller 47 carried by the lever system 31-33. The upper ends of the legs of the U-shaped trip member 231 are rigidly joined by a rod 245, which, when the trip member is released, strikes the latch levers 209 a sharp blow to start the latch roller 217 in tripping direction.

The means for releasing the trip member 231 consists of an electromagnet 247 comprising an E-shaped fixed core member 249 mounted between the spaced sides of a U-shaped bracket 251 only one side of which is shown. An energizing winding 253 is mounted on the center leg of the fixed core 249 and a channel-shaped armature 255 is pivotally mounted on a pivot pin 257 supported in the sides of the U-shaped bracket 251. The right-hand end of the armature comprises a latch 259 which normally engages a cross bar 261 joining the lower ends of the legs 231 of the trip member.

The winding 253 may be energized from any suitable source in a known manner and, when energized, attracts the armature 255 to effect release of the trip member 231. The spring 235 immediately actuates the trip member and causes the rod 245 to strike the latch members 209 a blow starting the latch roller 217 in unlatching direction. As soon as the center of the latch roller 217 passes to the left of the center line 211-35 the force of the accelerating spring moves the lever system 31-33 in a clockwise or opening direction, the roller 47 moves upwardly and, acting on the roller 217, cams the latch 209 and the cross members 213 to their fully unlatched positions as indicated at 209' and 213'. Thereafter the roller 47 moves upwardly along the cross member 213 to approximately the position indicated at 47' (Fig. 4). Release of the right hand end of the inner levers 33 in the manner previously described, causes the left end of the levers 31-33 to move back to the full line position at which time the spring 225 restores the latch 209 and the roller 217 to latching position to thereafter restrain the left end of the lever system in the full line position. The interrupter proceeds to the full open position in the previously described manner. The trip member 231 is reset by means of a spring 263 as soon as the latch 209 is moved to its unlatching position and the left end of the lever system moves upwardly. The spring 263 has one end hooked over a spring stud 265 in the downwardly extending arm of the lever 241 and the other end hooked over a rod 267 supported in the brackets 61, 63. When the latch 209 moves to its unlatching position, the trip member 231 follows until the spring 235 goes solid. As soon as the roller 47 moves upwardly, the spring 263 rotates the lever 241 counterclockwise about its pivot 243 and this movement of the lever 241 acting through the now solid spring 235 rotates the trip member in a clockwise direction to reengage the cross member 261 with the latch 259. Movement of the roller 47 to the full-line position (Fig. 4)

operates the lever 241 to again tension the springs 235 and 263.

The operation of the dump valve 163 by the latch 209 is the same as that previously described, the dump valve being opened and closed only once during a normal opening and closing operation of the interrupter.

The interrupter may be closed by compressed gas in the previously described manner and may also be closed manually by the manual closing device as previously described.

Having described several embodiments of the invention in accordance with the patent statutes, it is to be understood that various changes and modifications may be made in the particular embodiments disclosed without departing from some of the essential features of the invention.

We claim as our invention:

1. In a circuit interrupter comprising relatively movable contacts, operating mechanism for said contacts comprising a lever operatively related to said contacts, means releasably restraining one end of said lever, trip means operable in response to abnormal circuit conditions to release said one end of said lever to initiate opening movement of said interrupter, a second restraining means for releasably restraining the other end of said lever, means for operating said second restraining means to effect movement of said interrupter to full open position, spring means associated with said one end of said lever for limiting movement of said one end of said lever in opening direction, and manually operable means for rendering said spring means ineffective to limit movement of said one end of said lever.

2. In a circuit interrupter comprising relatively movable contacts, operating mechanism for said contacts comprising a lever operatively related to said contacts, means releasably restraining one end of said lever, trip means operable in response to abnormal circuit conditions to release said one end of said lever to initiate opening movement of said interrupter, a second restraining means for releasably restraining the other end of said lever, means for operating said second restraining means to effect movement of said interrupter to full open position, spring means connected to said one end of said lever for limiting the movement of said one end in opening direction and for reengaging said one end of said lever with said restraining means, means releasably restraining said spring means under tension, and manual means operable to release said restraining means to thereby render said spring means ineffective.

3. In a circuit interrupter, operating means comprising a lever movable to close the interrupter, compressed gas operated means for actuating said operating means to close the breaker, latch means engaging said lever to releasably restrain said operating means in closed position, trip means operable to effect unlatching movement of said latch means and opening of said operating means, a large exhaust valve for quickly exhausting the gas pressure from said compressed gas operated means to permit high speed opening movement of said operating means, means at all times connecting said exhaust valve to said latch means for movement therewith, and means for holding said latch means in unlatching position for a predetermined time following an unlatching movement thereof.

4. In a circuit interrupter, operating means comprising a lever movable to close the interrupter, compressed gas operated means for ac-

tuating said operating means to close the breaker, latch means engaging said lever to releasably restrain said operating means in closed position, trip means operable to effect unlatching movement of said latch means and opening of said operating means, a large exhaust valve for quickly exhausting the gas pressure from said compressed gas operated means to permit high speed opening movement of said operating means, means at all times connecting said exhaust valve to said latch means for movement therewith, said exhaust valve being closed when said latch means is in latching position and open when said latch means is in unlatching position, and means for holding said latch means in unlatching position for a predetermined time.

5. In a circuit interrupter, operating means movable to close the interrupter, compressed gas operated means comprising a cylinder and a piston operable therein for actuating said operating means to close the interrupter, means connecting said piston to said interrupter at all times for movement therewith, latch means releasably restraining said operating means in closed position, trip means for operating said latch means to effect opening of said interrupter, a large exhaust valve connected at all times for movement with said latch for quickly exhausting the compressed gas from said cylinder to permit high speed reverse movement of said piston and opening movement of said interrupter, and means on said operating means for maintaining said latch in unlatching position and for maintaining said exhaust valve in open position for a predetermined time following operation of said trip means.

6. In a circuit interrupter, operating means comprising a lever movable to close the interrupter, compressed gas operated means comprising a cylinder and a piston operable therein to cause said operating means to close the interrupter, latch means releasably restraining one end of said lever, a trip device for operating said latch to initiate an opening operation of said operating means, means comprising an exhaust valve connected at all times for movement with said latch means and operated by said latch means to quickly exhaust the gas pressure from said cylinder to permit high speed opening of said interrupter, means releasably restraining the other end of said lever, said restraining means being operable by said lever to release said other end of said lever to effect movement of the interrupter to full open position, and means for returning said one end of said lever to latched position upon release of said other end of said lever.

7. In a circuit interrupter, operating means for said interrupter comprising a lever, power operated means for actuating said operating means to close the interrupter, latch means releasably restraining one end of said lever, trip means for actuating said latch means to release said one end of said lever to thereby initiate opening movement of said interrupter, a second latch means releasably restraining the other end of said lever, means operable after said one end of said lever is released to cause the second latch to release the other end of said lever, means for returning said one end of said lever to latched position following release of said other end of said lever while permitting movement of said other end of said lever to full open position, means for releasably restraining said restoring means in operating position, and manual means

for rendering said restoring means inoperative to thereby permit said one end of said lever to move to full open position irrespective of the position of said other end of said lever.

5. In a circuit interrupter, operating means for said interrupter comprising a lever, power operated means for actuating said operating means to close the interrupter, latch means for releasably restraining one end of said lever, trip means for actuating said latch means to release said one end of said lever to initiate opening movement of said interrupter, a second latch means releasably restraining the other end of said lever, means operable after said one end of said lever is released to cause the second latch to release the other end of said lever, means for restoring said one end of said lever to latched position following release of said other end of said lever while permitting movement of said other end of said lever to full open position, means on said other end of said lever for receiving a manual closing means to permit manual movement of said other end of said lever and closing of said interrupter, and manual means for releasing said restoring means to thereby permit movement of said one end of said lever to full open position irrespective of the position of the other end of said lever.

9. In a circuit interrupter, operating means for said interrupter, a lever related to said operating means, a first latch releasably restraining one end of said lever in closed position, a second latch releasably restraining the other end of said lever in closed position, trip means operable to effect movement of said first latch to release said one end of said lever, means operable after said one end of said lever is released for actuating said second latch to release the other end of said lever, spring means for limiting the travel of said one end of said lever in opening direction and for restoring said one end of said lever to latched position, and manual means for releasing said spring means to permit said one end of said lever to move to full open position irrespective to the position of said other end of said lever.

10. In a circuit interrupter, operating means for said interrupter, a lever related to said operating means, a first latch releasably restraining one end of said lever in closed position, a second latch releasably restraining the other end of said lever in closed position, trip means operable to effect movement of said first latch to release said one end of said lever, means operable after said one end of said lever is released for actuating said second latch to release the other end of said lever, spring means having one end operatively related to said one end of said lever for limiting the travel of said one end of said lever in opening direction and for restoring said one end of said lever to latched position, means releasably restraining the other end of spring means, and manual means for releasing said other end of said spring means to permit said one end of said lever to move to full open position irrespective of the position of said other end of said lever.

11. In a circuit interrupter, operating means for said interrupter, a lever related to said operating means, a fluid motor related to said operating means for closing said interrupter, latching means comprising a first latch for releasably restraining one end of said lever in closed position and a second latch for releasably restraining the other end of said lever in closed position, a large exhaust valve connected to said first latch for movement therewith, trip means

operable to effect movement of said first latch to unlatching position and movement of said exhaust valve to open position to quickly exhaust the compressed gas from said motor and permit movement of said interrupter to open position, means for operating said second latch to release the other end of said lever, means for limiting the movement of said one end of said lever in opening direction and for then restoring said one end to closed position, and means on said one end of said lever for maintaining said first latch in unlatching position and for maintaining said exhaust valve in open position until said one end of said lever is restored to closed position.

12. In a circuit interrupter, operating means for said interrupter including a lever, power operated means for closing said interrupter, latch means for releasably restraining said lever in closed position, said latch means comprising a first roller on one end of said lever, a pivoted latch member, a second roller on said latch member for engaging said first roller to releasably restrain said lever in closed position, and trip means for actuating said latch member to effect disengagement of said rollers to release said lever and thereby initiate opening movement of said interrupter, and means on said latch member engaging said first roller when said lever is out of closed position to hold said latch member in unlatching position.

13. In a circuit interrupter, operating means for said interrupter including a lever, power operated means for closing said interrupter, latch means for releasably restraining said lever in closed position, said latch means comprising a first roller on one end of said lever, a pivoted latch member, a second roller on said latch member for engaging said first roller to releasably restrain said lever in closed position, trip means for actuating said latch member to effect disengagement of said rollers to thereby initiate opening movement of said interrupter, an extension on said latch member cooperating with said first roller to retain said latch member in unlatched position, and adjustable means for adjusting the relative positions of said rollers in the closed position of said lever.

14. In a circuit interrupter, operating means for said interrupter comprising a lever, power operated means for closing said interrupter, latch means for releasably restraining said interrupter in closed position comprising a roller on said lever, a pivoted latch member, a second roller on said latch member engaging said first roller to releasably restrain said lever in closed position, a trip member for actuating said latch member,

means releasably restraining said trip member, electro-responsive means operable when energized to cause release of said trip member, a first energy storage device for operating said trip member to effect unlatching movement of said latch member, and a second energy storage device for operating said first energy storage device to reset said trip member.

15. A circuit interrupter including a lever movable to close said interrupter, compressed gas operating means for actuating said lever to close said interrupter, a latch releasably restraining said lever in closed position, trip means operable to effect unlatching movement of said latch and opening of said interrupter, valve means for exhausting the gas pressure from said compressed gas operated means to permit high-speed opening movement of said interrupter, a connection responsive to unlatching movement of said latch whenever said latch is moved to unlatch said lever to open said valve means, said connection being responsive to movement of said latch whenever said latch is moved into latching engagement with said lever to close said valve, and means on said lever for holding said latch means in unlatching position and for holding said valve in open position for a predetermined time following an unlatching operation.

16. A circuit interrupter comprising compressed gas operated operating means for closing said interrupter, a latch releasably restraining said operating means in circuit closed position, a trip device for actuating said latch to unlatching position, valve means for admitting compressed gas to said operating means to close said interrupter, an exhaust valve for exhausting the gas pressure from said compressed gas operating means, means directly responsive to unlatching and latching movement of said latch to open and close said exhaust valve, and means on said operating means for maintaining said latch in unlatching position and for maintaining said valve in open position for a predetermined time following a tripping operation.
